UNITED STATES PATENT OFFICE

LAWRENCE W. LUFF, OF SHAKER HEIGHTS, OHIO, ASSIGNOR TO THE CONSOLIDATED IRON-STEEL MANUFACTURING COMPANY, OF CLEVELAND, OHIO, A CORPORATION OF OHIO

BOILER STAND

Application filed November 23, 1929. Serial No. 409,305.

This invention relates to boiler stands of the type employed for supporting a domestic hot water boiler.

The objects of the present invention are 5 to provide a novel form of such stand which shall be of extreme simplicity and of economic manufacture, and more particularly to provide such a stand of a minimum number of principal parts.

10 Another object of the invention is to provide such a form of said parts that a large number of the same may be conveniently cast in closely spaced relation in a single mold. And still another object of the invention is to provide by an arrangement of extreme simplicity, means for adjusting the stand to accommodate various boiler sizes.

The exact nature of my invention together with further objects and advantages thereof 20 will be apparent from the following description taken in connection with the accompanying drawings in which Fig. 1 shows in elevation, arranged in corresponding relation, the three principal parts from which my stand 25 is assembled; Figs. 2 and 3 are plan and elevation views respectively of the stand assembled to accommodate one of the possible sizes of boiler; Fig. 4 is a section as in the plane of line 4—4, Fig. 2; Figs. 5 and 6 correspond 30 generally with Figs. 1 and 2 showing however a modification of my invention; Fig. 7 is a detail showing the parts appearing in Fig. 6 adjusted to an optional relation; and Fig. 8 is a plan view of the part E appearing in 35 Fig. 5.

With reference now to the drawings and particularly now to Figs. 1—4 thereof, my boiler stand is assembled from three principal parts A, B, and C. These parts are 40 generally similar although not identically so as will appear. Each part however comprises a leg member 1 and a straight integral arm member 2 extending perpendicularly therefrom.

45 One end of each leg member 1 is notched as at 3 to receive and thus position the rim of a boiler as will appear.

The several arm members are arranged in different but adjacent planes when the leg 50 members of the parts are aligned as indicated

Fig. 1. Thus the arm member 2a is arranged in the plane intermediate those of the arm members 2b and 2c.

Each of the arm members has in its end portion a plurality of openings, 4, 5 and 6, 55 three being shown, spaced therealong. The series of openings of each arm corresponds with those of the other arms, that is, the openings 4 of the arms are all equidistant from their respective leg members 1, and likewise the openings 5 and 6 in each of the arms correspond in distance from their respective leg members. Thus each arm 2 has one of a set of openings 4, one of a set of openings 5, and one of a set of openings 6.

60 From what has thus far been described it will be apparent that the parts A, B and C may be assembled as indicated Figs. 2 and 3 by a securing member D, indicated as a bolt, extending through the several openings of 65 any of the described sets thereof. It will also be apparent that with the arms 2 of the parts spaced at 120° as indicated Fig. 2, the legs 1 will be equally spaced to define a cylinder of which the securing member D is central, 70 so that the notches 3 of the legs will lie equally spaced in the corresponding circle to receive the edge flange of a boiler to be supported.

75 As indicated Fig. 2 the set of openings numbered 6 is employed by aligning the same 80 to receive the member D. The central set of openings numbered 5 might be similarly employed to reduce the size of the circle defined by the notches 3, to accommodate a boiler of 85 smaller diameter; and the third set of openings 4 might be similarly employed to reduce the size of the circle defined by the notches 3, to accommodate a boiler of still smaller diameter.

80 In order to maintain the angularity of the arms 2 as indicated in Fig. 2, when the parts are assembled, I provide interlocking means 90 upon the contacting faces of the arms. The interlock comprises a corrugation-like face formation 7 on the end portion of each arm 2, 95 in which the openings 4, 5 and 6 are located. As indicated particularly in Figs. 2 and 4 these corrugation formations are arranged on the lower face of the arm 2b, both faces of the arm 2a, and the upper face only of the arm 2c. 100

Also as indicated the corrugation formations on all of the arms are arranged to extend in the same direction when the parts are properly assembled. It will be noted that by this arrangement a proper interlock is had regardless of the size to which the boiler stand is adjusted.

With reference now to Figs. 5-7 inclusive of the drawings wherein similar or corresponding parts are designated by similar or corresponding reference characters to those appearing in Figs. 1-4, it will be observed that the parts E, F and G and their general assembled arrangement are substantially similar to what has been disclosed with reference to parts A, B and C. The principal exception is that here the leg 2g of one of the three principal parts is longer, whereas the legs 2e and 2f of the other two principal parts are shorter, than before. Also the interlocking deformations 7 run transversely of the arms 2e and 2f for interengagement therebetween, and run lengthwise of the arm 2e and transversely of the arm 2g for interengagement therebetween as indicated. Thus the parts are assembled here with their arms in cruciform arrangement and rectangular relation as indicated Fig. 6, to locate the notches 3 of their legs 1 in the circumference of a circle as indicated in dot-dash lines at 9. In Fig. 6 the securing member D is arranged in the set of openings 4, whereby the stand is adjusted to accommodate the smallest size of boiler. As shown in Fig. 7 the member D may instead be secured in the set of openings 6 of the arms 2, obviously providing an adjustment to accommodate the largest size of boiler. Likewise were the openings 5 aligned and the member D secured therethrough, the adjustment to an intermediate size would be had.

It will be observed that the openings in the arm of the member G have greater spacing than those in the arms of the members E and F. The spacing of all of these openings is such that in every adjusted position of the parts, the notches 3 will be spaced 120° apart in the circle defined thereby.

What I claim is:

1. An adjustable boiler stand comprising, in boiler-supporting position, a plurality of circumferentially spaced vertical leg members and a corresponding plurality of arm members each extending radially inwards from its leg member, the adjacent ends of said arm members being arranged in parallel stacked relation, each arm member having a plurality of through openings spaced therealong, and a central securing member extending through a corresponding opening of each arm member to maintain the parts in the described relation, said securing member being adapted to extend through any corresponding set of said openings, one in each arm member, to adjust the leg members in

radial relation one arm having corrugations on a lower portion thereof, another arm having corrugations on an upper portion thereof and a third arm having corrugations on both upper and lower portions thereof, the corrugations of one arm meshed with those of another to maintain said arms in predetermined angular relation against rotation in either direction at all radial adjustments.

2. An adjustable boiler stand comprising, in boiler-supporting position, a plurality of circumferentially spaced vertical leg members and a corresponding plurality of arm members each extending radially inwardly from its leg member, the adjacent ends of said arm members being arranged in parallel stacked relation, each arm member having an opening therethrough, and a securing member extending through all of the openings to maintain the parts in the described relation and to maintain the arms against relative movement radially, one arm having corrugations on a lower portion thereof, another arm having corrugations on an upper portion thereof and a third arm having corrugations on both upper and lower portions thereof, the corrugations of one arm meshed with those of another to maintain said arms in predetermined angular relation against rotation in either direction.

In testimony whereof I hereby affix my signature.

LAWRENCE W. LUFF.
